Attorneys.

Patented Apr. 30, 1929.

UNITED STATES PATENT OFFICE.

CARLOS F. WHEATON, OF MINNEAPOLIS, MINNESOTA.

DOOR-HOLDING DEVICE.

Application filed May 7, 1928. Serial No. 275,619.

My invention relates to door holding devices and an object is to provide a device which will not only prevent doors such as garage doors from being blown shut when they are open but which will also tend to prevent them from swinging open when they are closed. I accomplish the objects of my invention by providing a device embodying a spring which is placed under tension when the door is swung either from open position toward closed position or from closed position toward open position, the spring being so connected that it passes over dead center when the door is in partly open position.

The full objects and advantages of my invention will appear in connection with the detailed description thereof, and the novel features of my inventive idea will be particularly pointed out in the claims.

In the accompanying drawings which illustrate a practical embodiment of my invention, Fig. 1 is a view in section showing the device on the line 1-1 of Fig. 3 and showing in full lines the position of the device when the door is closed. Fig. 2 is a view corresponding to Fig. 1 but showing the position of the device when the door is in opened position. Fig. 3 is a view on an enlarged scale in section on the line 3-3 of Fig. 1. Fig. 4 is a plan view of an attaching plate showing the opposite side thereof from that shown in Fig. 1. Fig. 5 is a detail view showing the use of a buffer.

As shown in the drawings, I provide an attaching plate 10 having a number of holes 12 therein for securing it in place. Near one edge of this plate, there is an offset portion 14 containing an elongated slot 16. A slideable stop 18 is held in adjusted position along the slot by a bolt 20 passing through the slot and the stop. Near the opposite edge of the plate and near one corner thereof, there is a boss 22 which is raised to such an extent as to bring it on a level with the offset portion 14. The boss 22 is provided with a central hole through which passes a rivet 24, this rivet also passing through a hole in one end of a bar 26 whereby this bar is pivoted to the plate. The other end of the bar 26 is pivotally attached to one end of a bar 28 by means of a rivet 30. The other end of the bar 28 is pivotally attached to a securing bracket 32 by a rivet 34. The bar 26 between its ends is provided with a projection 36 while the plate 10 at one of its corners is provided with a projection 38. The projections 36 and

38 are connected by a coiled spring 40. In installing the device, the plate 10 by means of fastening devices extending through the holes 12 is secured to the underside of a horizontal member H of the building, this horizontal member being located adjacent the upper edge of the door D. The plate 10 as shown in Fig. 1, is secured to the member H near the hinged margin of the door. The bracket 32 is secured to the door D in such position that the parts of the device when the door is closed have the position shown by full lines in Fig. 1 and with the spring 40 not under tension or under only slight tension. The stop 18 is adjusted to such position that the bar 26 will contact therewith when the door is swung open to the position which it is desired it to have when opened to its full extent. The offset portion 14 of the plate 10 permits the stop 18 to be slid when the bolt 20 is loosened. The provision of the boss 22 permits the bar 26 to swing past part of the offset portion 14 and into contact with the stop 18 as will be understood from Figs. 2 and 3. When the door is in closed position as shown in Fig. 1, the spring 40 tends to hold it closed. When the door is swung into the dotted line position shown in this figure, the bar 26 is caused to assume a position parallel with the length of the plate 10 and the spring 40 which has been tensioned by the opening movement is about to pass over dead center. When the spring has passed dead center, the tension thereof tends to swing the door into open position as shown in Fig. 2 and the spring acts to prevent the door from being blown shut. As shown in Fig. 5, the adjustable stop may be made in the form of a buffer for use in connection with heavy doors. The bolt 20 in this construction adjustably holds a plate 40 having flanges 44 and 46 on its two opposite ends. A rod 48 passes slidably through the flange 44 while this rod has a head 50 extending slidably through the flange 46 and normally projected beyond the flange 46 by a coiled spring 52 surrounding the rod 48 and interposed between the flange 44 and the head 50. When the door is swung into open position, the bar 26 engages the head 50 so that the shock is cushioned due to the fact that the head 50 is resiliently backed up by the spring 52.

I claim:

1. A door holding device comprising a plate adapted to be secured to a fixed part of

an article provided with a door, said plate having an offset portion provided with a longitudinal slot, a stop member adjustably secured along said slot, a bar pivoted to said plate, a second bar pivoted to said first bar, an attaching member pivoted to the outer end of said second bar for attachment to the door, and a spring attached to said first bar in such manner that the spring passes over dead center when said first bar is substantially parallel to the length of said plate, said first bar engaging said stop member when the door is fully open.

2. A door holding device comprising a plate adapted to be secured to a fixed part of an article provided with a door, said plate having an offset portion provided with a longitudinal slot, a stop member adjustably secured along said slot, a boss carried by said plate and which is raised to such an extent as to bring it on a level with said offset portion, a bar pivoted to said boss, a second bar pivoted to said first bar, an attaching member pivoted to the outer end of said second bar for attachment to the door, and a spring attached to said first bar in such manner that the spring passes over dead center when said first bar is substantially parallel to the length of said plate, said first bar engaging said stop member when the door is fully opened.

3. A door holding device comprising a plate adapted to be secured to a fixed part of an article provided with a door, a bar pivoted to said plate, a second bar pivoted to the outer end of said first bar, an attaching member pivoted to the outer end of said second bar for attachment to the door, a projection extending out from said plate, a second projection extending out from an intermediate point of said first bar, and a coiled spring connecting said projections in such manner that the

spring passes over dead center when said first bar is substantially parallel to the length of said plate.

4. A door holding device comprising a plate adapted to be secured to a fixed part of an article provided with a door, said plate having an offset portion at one of its edges provided with a longitudinal slot, a stop member adjustably secured along said slot, a bar pivoted to said plate at one of its corners opposite said edge, a second bar pivoted to said first bar, an attaching member pivoted to the outer end of said second bar for attachment to the door, and a coiled spring attached at one end to the other corner of said plate opposite said edge and attached at its other end to an intermediate point of said first bar.

5. A door holding device comprising a plate adapted to be secured to a fixed part of an article provided with a door, said plate having an offset portion provided with a longitudinal slot, a plate adjustably secured along said slot, said plate having flanges at both of its ends, a rod extending slidably through one of said flanges, a head for said rod extending slidably through the other of said flanges, a coiled spring normally holding said head projected beyond the flange through which it passes, a bar pivoted to said plate, a second bar pivoted to said first bar, an attaching member pivoted to the outer end of said second bar for attachment to the door, and a spring attached to said first bar in such manner that said spring passes over dead center when said first bar is substantially parallel to the length of said plate, said first bar engaging said head when the door is fully open.

In testimony whereof I hereunto affix my signature.

CARLOS F. WHEATON.
